UNITED STATES PATENT OFFICE.

OTTO BRINTZENHOFE, OF CLEVELAND, OHIO, ASSIGNOR TO ELECTRIC VACUUM
CLEANER COMPANY, INC., A CORPORATION OF NEW YORK.

DESIGN FOR A DUST-BAG OF A SUCTION-CLEANER.

5,6414.

Specification for Design.

Patented Oct. 26, 1920.

Application filed July 30, 1920. Serial No. 400,241. Term of patent 14 years.

To all whom it may concern:

Be it known that I, OTTO BRINTZENHOFE, a citizen of the United States, residing at Cleveland, county of Cuyahoga, and State of Ohio, have invented a new, original, and ornamental Design for a Dust-Bag of a Suction-Cleaner, of which the following is a specification, reference being had to the accompanying drawing, forming part thereof. Referring to the drawing, Figure 1 is

a plan view of a deflated dust bag embodying my design, and Fig. 2 is a similar view looking at the same from the opposite side.

What I claim is:—

The ornamental design for the dust bag of a suction cleaner, as shown.

In witness whereof, I have hereunto set my hand this 28th day of July, 1920.

OTTO BRINTZENHOFE.
